UNITED STATES PATENT OFFICE.

EDWARD MARSON, OF LONDON, ENGLAND.

DESIGN FOR A CLAMP-LEVER FOR TELESCOPIC SHOW-STANDS.

43,848.

Specification for Design.

Patented Apr. 15, 1913.

Application filed October 26, 1912. Serial No. 728,006. Term of patent 3½ years.

To all whom it may concern:

Be it known that I, EDWARD MARSON, a subject of the King of Great Britain and Ireland, and a resident of London, England, have invented a new, original, and ornamental Design for a Clamp-Lever for Telescopic Show-Stands, of which the following is a specification, reference being had to the accompanying drawing, in which—

Figure 1 is a side view of the clamp lever, and Figs. 2 and 3 are cross sections on the lines 2—2 and 3—3 respectively of Fig. 1.

One end of the lever is inclined at an obtuse angle to the body of the same, and the latter is curved in cross section through-

out its length. The lever is shown in full lines in conjunction with a ring or collar to which it is in practice hinged, and constitutes an attachment of a hollow stand which serves as a support for a telescopic rod upon which articles are supported and displayed for sale.

I claim:—

The ornamental design for a clamp lever for telescopic show stands, as shown.

EDWARD MARSON.
